UNITED STATES PATENT OFFICE.

DANIEL CAMPBELL, OF EAST LIVERPOOL, OHIO.

WINDOW-SHADE HANGER.

SPECIFICATION forming part of Letters Patent No. 782,484, dated February 14, 1905.

Application filed August 29, 1904. Serial No. 222,610.

To all whom it may concern:

Be it known that I, DANIEL CAMPBELL, a citizen of the United States, residing at East Liverpool, in the county of Columbiana and State 5 of Ohio, have invented certain new and useful Improvements in Window-Shade Hangers, of which the following is a specification.

This invention relates to means for hanging window-curtains to the upper portion of window-frames; and the object of the invention is to provide a supporting means of a peculiar form adapted to be attached to the window so as to be readily removable therefrom in order that the support may be raised or lowered bodily after the curtains have been secured thereto, and thus obviate the necessity for use of a ladder or similar device in hanging the curtains, the last method being that commonly practiced and subject to disadvantages 15 very apparent.

For a full description of the invention and the merits thereof and also to acquire a knowledge of the details of construction of the means for effecting the result reference is to be had 25 to the following description and accompanying drawings.

While the essential and characteristic features of the invention are susceptible of modification, still the preferred embodiment of the 30 invention is illustrated in the accompanying drawings, in which—

Figure 1 is a rear perspective view showing a device embodying the invention. Fig. 2 is a vertical sectional view, partially broken 35 away, the invention being shown in operative position, the upper portion of the window being shown in dotted lines. Fig. 3 is a perspective view of the curtain-hanger, the outer clamp-bars thereof being shown spaced. Fig. 40 4 is a detail view of a pole of a form adapted to raise and lower the curtain hanger or support.

Corresponding and like parts are referred to in the following description and indicated 45 in all the views of the drawings by the same reference characters.

The hanger proper, which directly supports the curtain or curtains, consists of inner and outer clamp-bars 1 and 2, respectively. The 50 clamp-bars 1 and 2 are disposed transversely

of the window-frame 3 when the hanger is in place, and these bars may be made of any suitable material—such as wood, metal, or the like—and surmounted with suitable ornamentation. The hangers are designed to be made in 55 different sizes corresponding with the fixed size of the window-frames, and meeting faces of the clamp-bars 1 and 2 receive the upper edge portions of the curtains therebetween. The clamp-bars 1 and 2 are normally held in co-operative relation by means now to be described. Projecting laterally from the end portions of the inner clamp 1 are horizontal arms 4, and these arms 4 are provided at their ends with engaging members in the form of 60 outstanding loops 5. The loops 5 extend approximately at a right angle from the arms 4, and the outer clamp member 2 is provided with spring members 6, engaging the loops 5 of the arms 4. The outer ends of the spring 65 members 6 are provided with eyes 7 to receive the bar or other part from which the loops 5 are formed. The engaging co-operation of the parts 5 and 6 of the hanger is such as to normally hold the bars 1 and 2 clamped against 70 each other, at the same time admitting of the spring movement of the outer clamp-bar away from the inner clamp-bar in securing the curtains to the hanger or in removing said curtains therefrom. The provision of the eyes 7 at the ends of the spring members 6 obviates the likelihood of accidental displacement 75 of outer bar 2 and also limits any lateral movement of said bar 2, holding the latter in proper relative position at all times.

The hanger is provided with supporting-hooks 8, projecting rearwardly from clamp-bar 1, and these hooks engage in suitable engaging devices 9, permanently secured to the upper portion of the window-frame 3, as 80 shown in Fig. 2, and lifting devices in the form of the pole 10 may be used to raise the hanger in securing the same to the window-frame 3, said pole having a hook 11, engaging in an eye member 12, secured to the inner 85 clamp-bar upon the upper portion thereof. Eye-screws 13 project downwardly from the end of the clamp-bar 1, and suitable cords may be attached to the eyes of said screws, so as to provide convenient means for draping 90 100

the curtains after same have been attached to the hanger. The clamp-bars 1 and 2 are provided upon their meeting faces with a matching tongue 14 and groove 15, so that said bars 5 will effectually grip the curtains when the upper portions of the latter are received therebetween. The outermost portions of the loops 5 are slightly in rear of the plane of the outer side of the member 2, so that the spring members 6, which project from the ends of the clamp-bars 2, must be sprung rearward in securing the same in engagement with the respective loops 5 adjacent.

It will be understood that in putting up the 15 curtains the same will project proportionally when attached to the hanger, after which said hanger can be readily raised to a supported position at the upper portion of the window-frame 3, the curtains assuming proper positions when suspended therefrom. The curtains may be quickly lowered for cleaning purposes or the like by proper manipulation of pole 10, and much of the time and labor usually expended by the present methods of 25 hanging curtains is avoided.

The members 4 and 6 preferably constitute the ends of bars or rods applied to the clamp-bars 1 and 2, though this construction is not necessary.

30 The parts 8 of course hold the bar 1 hard against the side portions *a* of the window-frame, and thus rigidly position the whole supporting device.

Having thus described the invention, what 35 is claimed as new is—

1. In a window-curtain hanger, the combination of inner and outer clamp-bars, arms extended from the ends of the inner clamp-bar, engaging members carried by said arms,

and spring members projected from the ends 40 of the outer clamp-bar and coöperating with the engaging members aforesaid.

2. In a window-curtain hanger, the combination of inner and outer clamp-bars, horizontal arms extended from the ends of the 45 inner clamp-bar, engaging members projecting at an angle to the arms, spring members extended from the ends of the outer clamp-bar and engaging the engaging members aforesaid, and means for attaching the hanger to 50 the window-frame.

3. In a window-curtain hanger, the combination of inner and outer clamp-bars, horizontal arms extended from the ends of the 55 inner clamp-bar, engaging loops projected from said arms, spring members projected laterally from the ends of the outer clamp-bar and engaging the loops aforesaid, and means for attaching the holder to the window-frame.

4. In a window-curtain hanger, the combination of inner and outer clamp-bars, horizontal arms extending from the ends of the 60 inner clamp-bar, engaging loops projected outwardly from the ends of said arms, spring members projecting horizontally from the 65 ends of the outer clamp-bar and provided with eyes engaging the loops aforesaid, supporting-hooks projected rearwardly from the inner clamp-bar for attachment thereof to the window-frame, and a supporting member projected upwardly from the inner clamp whereby the hanger may be raised or lowered. 70

In testimony whereof I affix my signature in presence of two witnesses.

DANIEL CAMPBELL. [L. s.]
